UNITED STATES PATENT OFFICE.

KARL D. SMITH, OF BATTLE CREEK, MICHIGAN, ASSIGNOR TO UNION STEAM PUMP COMPANY, OF BATTLE CREEK, MICHIGAN.

PUMP.

1,384,928.

Specification of Letters Patent. Patented July 19, 1921.

Application filed March 6, 1917. Serial No. 152,810.

To all whom it may concern:

Be it known that I, KARL D. SMITH, a citizen of the United States, residing at Battle Creek, county of Calhoun, State of Michigan, have invented certain new and useful Improvements in Pumps, of which the following is a specification.

This invention relates to improvements in pumps.

10 My improvements are especially designed by me for embodiment in dry system pumps, that is, pumps for handling air only, and I have illustrated the same as I have embodied them for such purpose. My improved pump is adapted for either pressure or vacuum systems.

The main objects of my invention are:

First, to provide an improved pump in which the passages and ports, valve seats and valve chambers, are easily formed and readily accessible.

Second, to provide an improved pump in which the valves are in the form of flat annular steel disks with slight lift or movement, making it possible to operate the machine at high speed without noticeable noise, and at the same time, one having a large free portage.

Third, to provide an improved pump which retains its efficiency when operated at high speed.

Further objects, and objects relating to structural details, will definitely appear from the detailed description to follow.

35 I accomplish the objects of my invention by the devices and means described in the following specification. The invention is clearly defined and pointed out in the claims.

40 A structure which is a preferred embodiment of my invention is clearly illustrated in the accompanying drawing, forming a part of this specification, in which:

Figure I is an elevation of a pump embodying the features of my invention, a portion of the cylinder wall being broken away.

Fig. II is an enlarged detail section, taken on a line corresponding to line 2-2 of Fig. I.

50 Fig. III is a plan view of the inner head member.

Fig. IV is a plan view of the outer head member.

55 In the drawing, similar reference characters refer to similar parts throughout the

several views, and the sectional view is taken looking in the direction of the little arrows at the ends of the section line.

Referring to the drawings, the embodiment illustrated is a single action pump 60 comprising a cylinder 1, and reciprocating piston 2 provided with a connecting rod 3. Means for driving the crank shaft 4 are not shown, as they form no part of my present invention, and suitable means will be readily 65 understood.

The cylinder head comprises superimposed members 5, 6 and 7. The inner member is preferably in the form of a flat plate and is provided with an inlet passage 8 delivering to an annular centrally disposed inlet chamber 9. In the upper face of the head member 5 is a recess 10 provided with an annular inlet valve seat 11, there being a central depression 12 within this valve 70 seat. The superimposed head member 6 coacts with the head member 5 in providing an annular inlet valve chamber; the superimposed head member having a depending stem 13 projecting into the depression 12. 80 This inlet valve chamber is connected to the inlet chamber 9 by a plurality of ports 14 disposed in an annular series and opening into the valve seat 11, as clearly shown in Fig. III. The inlet valve chamber is connected with the cylinder by an annular series of ports 15. The superimposed head member 6 is provided with a discharge valve chamber 16 having a discharge passage 17 and an annular valve seat 18 into which an 90 annular series of discharge ports 19 open. The discharge ports also communicate with the inlet valve chamber.

For convenience in forming and assembling the parts the head member 6 has an 95 opening 20 in its top closed by the cap or outer member 21 which is threaded into the member 6.

Annular disk-like inlet and discharge valves 22 and 23, respectively, are arranged 100 on the inlet and discharge valve seats. To insure the prompt seating of the inlet valve 22 certain of the discharge ports 19 are counter-bored, as at 24, to receive the seating springs 25. The outer member 21 is 105 provided with a stem-like projection 26 which depends into a recess 27 in the member 6 so that it constitutes a guide stem for the discharge valve. A seating spring 28 is arranged on this stem. The head members 110

are secured together and to the cylinder by the screw bolts 29, the head members being provided with aligned openings 30 adapted to receive these bolts. By thus forming the 5 head members, ports and passages may be readily formed and the parts are economical to produce, also they are very conveniently assembled and disassembled as occasion requires.

10 By thus forming and arranging the parts I provide a free portage for the air and the valves have but little lift and are practically noiseless in operation. The structure is also adapted to be operated at high speeds without impairing the efficiency of the pump, 15 which not infrequently occurs in pumps of this character owing to the valve fluttering or failing to close properly at high speeds.

When it is desired to use the pump as a 20 vacuum pump the passage 8 is connected with the tank to be exhausted. When it is desired to use it as a pressure pump the connection is made with the passage 17.

I have illustrated and described my improvements in an embodiment which I have found very satisfactory. I have not attempted to illustrate or describe certain modifications in structural details which I contemplate, and which might be desirable 25 under certain circumstances, as I believe the disclosure made will enable those skilled in the art to which my invention relates to embody or adapt the same as conditions may dictate.

30 35 The broad claims presented in this application have been transferred to the applicant's copending application, Serial No. 49,274, filed September 7, 1915.

Having thus described my invention, what 40 I claim as new and desire to secure by Letters Patent, is:

1. In a structure of the class described, the combination with a cylinder, of a head therefor comprising a pair of superimposed head members, the inner head member being provided with an inlet passage, an annular

inlet chamber, an inlet valve chamber in its outer face provided with an annular valve seat, a plurality of inlet ports opening into said valve seat, and a plurality of cylinder ports opening to said inlet valve chamber, the superimposed head member constituting the top of said inlet valve chamber and being provided with a stem disposed centrally of said inlet valve seat and with a discharge valve chamber and discharge passage therefor and having an annular discharge valve seat and a plurality of discharge ports opening into said inlet valve chamber and said discharge valve seat, 55 annular disk-like valves disposed on said seats, a cap for said superimposed head member provided with a stem disposed centrally of said discharge valve seat, a coiled spring disposed on said stem on said cap to 60 seat said discharge valve, and a seating spring for said inlet valve.

2. In a structure of the class described, the combination with a cylinder, of a head therefor comprising a pair of superimposed head members, the inner head member having an inlet valve chamber in its outer face provided with an annular valve seat, a plurality of inlet ports opening into said valve seat, and a plurality of cylinder ports opening into said inlet valve chamber, the superimposed head member constituting the top of said inlet valve chamber and provided with a discharge valve chamber having an annular discharge valve seat and a plurality of discharge ports opening into said inlet valve chamber and said discharge valve seat, and annular disk-like valves disposed on said seats.

In witness whereof, I have hereunto set 85 my hand and seal in the presence of two witnesses.

KARL D. SMITH. [L.S.]
